UNITED STATES PATENT OFFICE.

ALFRED C. HAFELY, OF NEW YORK, N. Y.

BOOK-CLASP.

SPECIFICATION forming part of Letters Patent No. 374,674, dated December 13, 1887.

Application filed October 10, 1887. Serial No. 251,910. (No model.)

To all whom it may concern:

Be it known that I, ALFRED C. HAFELY, of the city and State of New York, have invented an Improvement in Book-Clasps, of which the 5 following is a specification.

Before my present invention a clasp for books had been made by myself and others in which a stationary screw with right and left hand threads, or a spring connected to one cover, 10 had been made to act upon two arms hinged together and adapted to receive at the hinge the stud or pin upon the other book-cover, the clasp acting to draw the book-covers toward each other as the ends of the hinged arms were 15 spread apart. The hinged arms, however, being exposed to view, are objectionable, especially with albums and expensive books. In my present invention I make use of a hinged box connected with one cover, a plate sliding 20 within the box and adapted to engage a stud upon the other cover, and a toggle arm or arms within the box and acting to draw the plate inwardly, and thereby close the book firmly.

25 In the drawings, Figure 1 is an elevation of a clasp with the cap-plate of the box removed. Fig. 2 is a cross-section of the parts as applied to the cover of a book. Figs. 3 and 4 are similar to Fig. 1, but illustrate modifications in the 30 arrangement of the toggle.

The clip-plates A B are of any desired character, and they are to be fastened upon the cover at the edges, as usual. The clip-plate B has a stud or hook, 2, that engages the plate D 35 when the clasp is closed. The box E is pivoted to the plate A by the ears 3, through which the screw or rod 4 passes, and this rod passes into or through the box E near one edge, and usually there are heads 5 to the rod 4, and such 40 rod is screw-threaded within the box E, and the plate D slides into the box E at its slotted outer edge. The toggle F is pivoted at 6 to the inner edge of the plate D, and at 7 to the nut I around the rod 4. If the rod 4 is screw-threaded with right and left hand threads, 45

there will be two nuts, I, and two diverging toggle-links, F, as seen in Fig. 1. If the rod 4 is screw-threaded in one direction only, the toggle-links F will be parallel, as illustrated in Fig. 3; or only one link, F, and one nut, I, 50 may be used, as seen in Fig. 4. In either instance the movement given to the nut or nuts I by the rotation of the screw-rod 4 draws the plate D inwardly, or forces it outwardly by changing the angle of the toggle-link or link 55 F, and thereby the clasp is made to either draw the book-covers toward each other or to allow the covers to separate for opening the book, and the movement of the plate D is rectilinear, and the parts that act upon the 60 same are out of sight and within the box E, and this box E and plate D can be made of any desired ornamental character, and they are strong and durable.

The sliding plate D can be partially or entirely inclosed by the box E, and such box E may be made without the cap-plate, if desired, the plate D being suitably connected to the other parts of the plate or box E.

I claim as my invention—

1. The combination, with the clip-plates A B and stud or hook 2, of the box E, pivoted to the clip A, the plate D, sliding within the box E, the screw-rod 4, nut I, and toggle F, connecting the nut I and plate D and serving 75 to move such plate in or out as the screw-rod is rotated, substantially as set forth.

2. The combination, with the clip-plates A B and stud or hook 2, of the box E, the sliding plate D, the toggle F, connected at one 80 end to the plate D, and mechanism, substantially as specified, for acting on the other end of the toggle and sliding the plate, as set forth.

Signed by me this 5th day of October, A. D. 1887.

ALFRED C. HAFELY.
